GAS STOVE

Lewis Moore and Isaiah S. Holloway, Joliet, Ill.,
 assignors to Moore Brothers Company, Joliet,
 Ill., a corporation of Illinois

Application January 30, 1932, Serial No. 587,726

1 Claim. (Cl. 126—37)

This invention relates to stoves and has more particular reference to ranges provided for cooking. While the invention will hereinafter be described as embodied in a gas cook stove, it will be readily appreciated that numerous other features are capable of valuable and advantageous use in stoves of other character and employing heat otherwise generated as from kerosene, electric units, etc.

One of the principal objects of this invention is to provide mechanical features of stove construction which may be employed to contribute to the production of a stove of improved appearance. In connection with this object of the invention it is mentioned that it is desired to produce a stove all of the operating portions of which, as for example the burners, burner tops, heat controls, etc., may be protected and hidden when the stove is not employed for cooking.

Another important object of the invention is the provision of a stove of this character which when not in use may have the appearance of an attractive and symmetrically designed cabinet with a flat table top of unbroken superficial area.

Another important object of the invention is the provision of a stove having door and other constructions of sturdy and durable construction, the hinges of which will be hidden from casual observation.

Numerous other objects and advantages of the invention will be apparent as it is better understood from the following description, which, when taken in connection with the accompanying drawings, illustrates a preferred embodiment thereof.

Referring to the drawings,—

Figure 1 is a perspective view of the stove embodying my present invention;

Fig. 2 is a similar view of the top of the stove, showing the table top elevated to expose the grill work of the burner top;

Fig. 3 is a partial perspective view of the stove, showing a compartment door in open position to expose the thermostatic and valve controls for the oven burners;

Fig. 4 is an enlarged partial detail showing the counter balance for the stove table top; and

Fig. 5 is a partial sectional view through the free edge of the stove table top, showing its connection to the brace members.

The stove shown on the drawings and embodying the present invention comprises a body having a flat back wall 21 and side walls 22 curved from the ends of the back wall around to the

front, where in accordance with the preferred embodiment of the invention they merge into a flat front part, indicated generally by reference character 23. This central flat front portion in the present instance comprises a broiler drawer or slide 24, the oven door 25, and the burner valve panel 26. The burner top generally indicated at 27 is arranged above the burner box of which the panel 26 provides the front wall.

A table top 28 is pivoted along the rear of the stove and is adapted to be arranged in the elevated position indicated in Fig. 2 to permit cooking upon the stove top, or to be swung down as indicated in Fig. 1 to serve as a table top of unbroken superficial area.

At each side of the portion of the stove containing the burner box, the oven and the broiler compartment, the combined end and front walls are provided with doors 29 and 31, which are hinged along vertical pivotal axes 32 and provide access to side compartments of the stove indicated respectively by reference character 34 (Fig. 3).

An oven broiler burner control is preferably arranged within the right hand compartment 34. This control comprises a thermostatic valve 43 adapted to be set by a handle 44. A main shut off valve 45 is provided, and pipes 46 and 47 lead down from the valves 43 and 45 to adjacent the broiler burner. 48 indicates the mixer of the broiler burner arranged through a suitable opening through the adjacent partition 49 in the stove.

The table top 28 is pivoted along the top of the flat rear wall of the stove and is adapted to be supported in vertical raised position. The table top preferably comprises a body sheet folded about its free edges as indicated at 81 to fit over the fixed top of the stove when the top is lowered. The table top is provided with a right angle flange 82 at its hinge edge, and angular members 83 are secured at 84 to the flange 82, and are pivoted at 85 in brackets 86, bolted at 87 to the fixed top of the stove. The brackets 86 are arranged beneath the top of the stove and extend rearwardly and through openings 88 in the back wall 21 of the stove.

A rod 89 is pivotally engaged at 91 in an arm 92 which extends downwardly and inwardly from near each end of the flange 82 of the movable stove top. Each rod 89 passes through an aperture 93 in a lug 94 which extends downwardly from the fixed stove top and beyond the lug 94 a spring 95 embraces the rod and bears against a washer 96 held on the end of the rod 55

by a nut 97. The spring 95 serves to counterbalance the movable stove top in its movement from closed to open position.

A brace member 98 is provided at each side of the stove and has one end 99 formed into a hook disposed through an opening 101 appropriately arranged in the fixed stove top. The other end of the brace rod 98 is hooked into a recess 102 in a small casting 103 arranged upon the front or underside of the movable table top and held in place by a screw 104 extending through the casting and the table top and into a flat button 105.

It will be manifested that the construction of all of the parts is such that they may be readily employed in association with each other to provide a stove of the attractive appearance shown upon the drawings, and that individually the several parts and features contribute to the provision of the stove of convenient and easy operation.

It is thought that the invention and many of its attendant advantages will be understood from the foregoing description, and it will be apparent that various changes may be made in the form, construction and arrangement of the parts without departing from the spirit and scope of the invention or sacrificing all of its

material advantages, the form hereinbefore described being merely a preferred embodiment thereof.

We claim:

In a stove having a sheet metal body provided with top and bottom frame portions and divided into central oven and broiler compartments and an upper burner compartment provided with a burner top, and side compartments disposed one on each side of said first mentioned compartments, a table top member hingedly connected to said top frame portion adjacent to its rear edge for vertical swinging movement, said top being co-extensive with said burner top and said side compartments when swung to its horizontal position, an ear provided on said hinged connection, a bracket member depending from said top frame member and provided with an aperture therein, a rod having one end pivotally connected with said ear and extending forwardly through the aperture in said bracket member, an abutment carried by the forward end of said rod, and a spring interposed between said abutment and said bracket member for yieldably opposing the downward swinging movement of said table top.

LEWIS MOORE,
ISAIAH S. HOLLOWAY.
